[57] CLAIM

The ornamental design for a ice cream cone, as shown and described.

DESCRIPTION

FIG. 1 is a top plan view of an ice cream cone showing my new design;

FIG. 2 is a cross-sectional view thereof, taken along line 2—2 of FIG. 1;

FIG. 3 is a bottom plan view thereof; and,

FIG. 4 is a front elevational view thereof, it being understood that the sides and rear elevational views are the same as the front.
